UNITED STATES PATENT OFFICE.

WILLIAM J. YOUNG, OF LYNN, MASSACHUSETTS.

HEEL-COMPRESSING MACHINE.

SPECIFICATION forming part of Letters Patent No. 628,512, dated July 11, 1899.

Application filed January 11, 1898. Serial No. 666,356. (No model.)

To all whom it may concern:

Be it known that I, WILLIAM J. YOUNG, a citizen of the United States, residing at Lynn, in the county of Essex and State of Massachusetts, have invented certain new and useful Improvements in Heel-Compressing Machines; and I do hereby declare the following to be a full, clear, and exact description of the invention, such as will enable others skilled in the art to which it appertains to make and use the same.

The present invention relates to boot and shoe machinery, and more particularly to machines for compressing and molding heels, such machines being generally known in the art as "heel-compressing machines."

The object of the present invention is to produce a heel-compressing machine of simple and compact form and of great power and capacity and to provide an improved feeding and ejecting mechanism to automatically feed the heel-blank to the dies and eject the same therefrom after it has been compressed.

To the above end the present invention consists of the devices and combination of devices which will be hereinafter described and claimed.

The present invention is illustrated in the accompanying drawings, in which—

Figure 1 is a front view of the machine. Fig. 2 is a side view of the machine, looking from the right of Fig. 1. Fig. 3 is a plan view of the machine. Fig. 4 is a horizontal sectional view above the table and dies. Figs. 5, 6, and 7 are details of the ejecting mechanism, to be described; and Figs. 8 and 9 are details of the male die or former.

Similar letters of reference refer to corresponding parts throughout the several views.

In the drawings, A represents the main frame, which may be of any usual or preferred construction, but which for strength is preferably formed of a front part a in a single casting, to the back of which are secured, as by the bolts a', the rear frames a². (See Figs. 2 and 3.)

Formed in the rear frames a² are suitable bearings a³, in which is mounted to rotate the main driving-shaft A', and in the upper part of said rear frames a² are suitable bearings a⁴, in which is mounted the crank-shaft A².

Upon the main shaft A' is mounted loosely

a driving-pulley A³, which is driven by a belt from any suitable source of power, said pulley being free to have a limited sliding movement along said shaft and being provided with a beveled clutch-face a⁵, which is arranged to be forced in contact with a beveled clutch-face a⁶, formed upon a wheel A⁴, fixedly secured to the shaft A'. The pulley A³ is arranged to be moved toward and from the wheel A⁴, to connect and disconnect the friction-faces a⁵ and a⁶, by any suitable mechanism, that shown in the machine of the drawings comprising a lever a⁷, which is fulcrumed at a⁸ to one of the rear frames a² and which is provided with a yoke or fork a⁹, which loosely engages the hub of the pulley A³ and which at its lower end is pivotally connected at a¹⁰ with a link a¹¹, which is in turn pivotally connected at a¹² with an arm a¹³, rigidly secured to the rear end of a rock-shaft a¹⁴, which is mounted to turn in suitable bearings a¹⁵ in the frame and which at its front end is provided with a foot-treadle a¹⁶, whereby said shaft a¹⁴ may be rocked to straighten and bend the toggle formed by the arm a¹³ and the link a¹¹, to thus through the lever a⁷ move the pulley A³ toward and from the wheel A⁴, whereby to control the movement of the machine. Upon the opposite end of the main shaft A' is a pinion a¹⁷, which is in gearing with a gear a¹⁸, which is fixed upon the end of the crank-shaft A², whereby motion is communicated from the main shaft A' to said crank-shaft A². Connected to an arm a¹⁹ of the rock-shaft a¹⁴ is a link a²⁰, which is connected to a band-brake a²¹, which may be of any usual or preferred construction and which is arranged to engage a brake-pulley a²², mounted upon the main shaft A'. (See Figs. 1 and 2.)

Arranged to slide vertically along suitable guideways b, formed along the inner side of the front frame a, is a bed or table B, which upon its upper surface carries a suitable tread-surface-molding plate b* and side-compressing dies D, as will be fully described. The bed or table B is arranged to be moved vertically by a toggle, it being pivotally connected at b' with the upper member b² of the toggle-levers b² and b³, the lower member b³ of the toggle-levers being fulcrumed at b⁴ to the frame a. The meeting ends of the toggles b² and b³ are provided with recesses b⁵,

in which the head b^9 of the connecting-rod b^{10} fits and engages the shaft b^5 , the opposite end of the connecting-rod b^4 having a suitable bearing b^{11} , fitted upon the crank b^{12} of the crank-shaft A^2 .

The above-suggested arrangement is such that a rotation of the main shaft A' will rotate the crank-shaft A^2 and by means of the crank b^{12} and the connecting-rod b^{10} alternately straighten and bend the toggles b^2 and b^3 , and thus impart a vertical reciprocation to the bed or table B toward and from the upper end of the frame a .

Upon the bed or table B is arranged the tread-face-molding plate b^* and the sliding side-compressing dies D , each of which has a curved face d , arranged to act upon and mold one-half of the sides and back of the heel, as usual in machines of this character. Each die D is removably secured by any suitable means, as by the plates d' , to the sliding die-carriers d^2 , which are arranged to have a sliding movement along the upper surface of the bed or table B in a guideway formed by the upwardly-projecting flanges d^4 , and such movement of the die-carriers may be produced by any suitable mechanism, that shown in the drawings being arranged and operating as follows:

30 D' represents a pair of levers which are fulcrumed at their upper ends at d^5 in suitable recesses a^* of the frame a , the lower ends d^6 of said levers being free and resting upon the upper surface of the bed or table B , outside 35 of the die-carriers d^2 , whereby upon the upward movement of the bed or table B the free ends d^6 of the levers D' may slide inwardly along said bed or table and engage the die-carriers d^2 , and upon a further upward movement of said bed or table force said die-carriers d^2 and the dies d toward each other to cause the dies to compress and shape the sides and ends of the heel-blank which may be between them.

45 In order that the dies D shall not be opened to the full extent of the movement of the ends d^6 of the levers D' along the bed or table B , but shall only open sufficiently to permit the placing of the heel-blank therein in 50 order to insure the proper positioning of the heel-blank and to avoid any possible displacement of the heel-blank upon the closing of said dies, the dies D are preferably disconnected from the levers D' and are arranged 55 to be moved by said levers only in one direction to close said dies around the heel-blank, said dies being moved in the opposite direction or in a direction to open them for the reception of a heel-blank by suitable springs 60 d^7 , which at one end are secured to said dies and at their opposite ends to the bed or table B , the die-carriers d^2 and the ends d^6 of the levers D' being provided with recesses d^8 , in which the springs d^7 are received.

65 In order that the ends d^6 of the levers D' may properly and securely engage the die-carriers d^2 upon the inward movement thereof

caused by the upward movement of the bed or table B , said ends are preferably rounded, as shown in Fig. 1, and engage rounded recesses d^9 , formed in the outer faces of the die-carriers d^2 . (See dotted lines, Fig. 1.)

Coöperating with the dies D is a male or heel-seat die C , which is preferably mounted for a yielding vertical movement in its holder and also to have a vertical adjustment toward and from the die D in order to accommodate the dies for different thicknesses of heels. The heel-seat die C is carried upon a stem c^* , which stem is held for vertical movement 80 within the screw-threaded holder c' by a pin c^2 , the upper end of the stem c^* being acted upon by a spring c^3 , which acts to normally press the heel-seat die yielding toward the dies D , whereby said heel-seat die C will contact yielding with the heel-blank before the dies D have entirely closed thereon, so that if said heel-blank has been improperly positioned the dies D may move it to one side or the other to center it, and the yielding contact of the heel-seat die C with said heel-blank will insure the proper holding of said blank in its adjusted position until the final pressure of the dies takes place.

The vertical adjustment of the heel-seat die C is obtained by the vertical movement of the screw-threaded holder c' , said holder being surrounded by a sleeve c^4 , which has an internal screw-threaded bearing fitting the threads of the screw-threaded holder c' , and said sleeve is mounted to rotate in a bearing c^5 of the frame a , it being supported in said bearing by a head c^6 , formed on its lower end, which rests in a bearing c^7 , formed in a plate c^8 , which is secured to the under side 105 of the frame a by bolts c^9 . The turning of the sleeve c^4 causes a vertical movement of the screw-threaded holder c' and a vertical adjustment of the heel-seat die C , the holder c' being provided with a squared head c^{10} , 110 which fits in a squared bearing c^{11} in the plate c^8 , whereby the holder c' is prevented from rotating upon the turning of the sleeve c^4 . The sleeve c^4 is arranged to be turned by a hand-wheel c^{12} , which is connected to a 115 shank c^{13} , which in turn is connected to the sleeve c^4 by a pin c^{14} . In order to compress the breast edge of the heel, there is provided a breastplate c^{14} , which is pivotally supported by a pin c^{15} upon the front of the head c^{10} , 120 passing down in front of the heel-seat die C and being normally pressed outwardly by a spring c^{16} . The lower end of the breastplate c^{14} is provided with a beveled finger c^{17} , whereby upon the upward movement of the bed or table B the lower end of the finger c^{17} will engage the inner edge of the plate c^{19} and move the breastplate c^{14} toward the front of the male die C , so that its lower end will be received in the recess c^{18} , and when the dies 125 are finally brought together the breastplate c^{14} will be forced against the breast of the heel to impart a molding pressure thereon.

The heel-blanks are automatically fed be-

tween the dies D to be compressed, and after being compressed are automatically ejected from the dies D from the same side of the machine at which they were fed into the dies, 5 any suitable chute or deflector being used to convey the compressed heel-blank to a barrel or other receptacle placed to receive them.

The mechanism for feeding the heel-blanks to the die D in the machine of the drawings 10 is preferably arranged as follows:

E represents a table, which is fixedly secured upon the front of frame a in any suitable manner, as by the bolts e. The table E is slotted, as at e', in line with the dies D, and 15 along this slot travels a feeding-plate e², said feeding-plate having an upturned end e³, or otherwise formed to engage and push the heel-blank forward between the dies D. The feeding-plate e² is connected by means of a link 20 e⁴ with a lever e⁵, said lever being fulcrumed at e⁶ to the under side of the table E. The lever e⁵ at its outer end is pivotally connected with a rod e⁷, which at its opposite end is pivotally connected at e⁸ with one arm e⁹ of a 25 bell-crank lever, which is fulcrumed at e¹⁰, the opposite arm e¹¹ of said bell-crank lever carrying a cam-roll e¹², arranged in the path of a tappet e¹³, held to rotate with the crank-shaft A², whereby a rotation of the shaft A² 30 will by means of the tappet e¹³ impart a quick oscillation to the bell-crank lever and by means of the rod e⁷ and the lever e⁵ impart a quick movement of the feeding-plate e² toward the dies D, to thus feed the heel-blank 35 along the table E between said dies. In order to quickly return the feeding-plate e² after the bell-crank lever has been released by the tappet e¹³, there is provided a spring e¹⁴, one end of which is connected to the lever e⁵ and 40 the other end to the fixed frame of the machine.

In order that there shall be no danger of breakage in case the forward movement of the feeding-plate e² should meet an obstruction, the rod e⁷ is made in two sections, one section being provided with a sleeve e¹⁵, in which the other section is arranged to slide, and within said sleeve e¹⁵ is a spring e¹⁶, which bears against the section of the rod sliding 45 therein. By this construction provision is made for lost motion and all danger of breaking the parts by an obstruction in the path of movement of the heel-blank-feeding plate which would stop the advance of said plate 55 is obviated.

The heel-blank to be fed between the dies D is placed upon the upper surface of the table E in front of the feeding-plate e², with its breast edge against the front of said plate, 60 and in order to insure the correct feeding of the blank a guide-plate e¹⁷ is adjustably secured upon the upper surface of the table E along and parallel with the line of movement of the feeding-plate e², said guide-plate being 65 secured by set-screws e¹⁸ passing through slots e¹⁹ in the guide-plate e¹⁷, whereby said

guide-plate e¹⁷ may be adjusted according to the size of heel being fed.

In order that there shall be no liability of the heel jumping over the back of and out of the dies D as it is fed thereto, there is provided a detent finger or plate f, which is arranged to have a horizontal sliding movement back and forth over the die-cavity between the dies D, the forward end of said detent-plate f being arranged to engage the upper surface of the back of the heel-blank as it is fed into position between the dies D. The detent-plate f is arranged to slide in a guideway f', formed in a plate f², which is bolted 80 to the top of the back flange d⁴, and it is reciprocated by any suitable means to cause its forward end to be projected over the dies D upon a lowering of the bed or table B and to be drawn back upon the upward movement 85 thereof out of the way of the heel-seat die C.

In the machine of the drawings the detent-plate f is actuated by a finger or lever f³, pivoted at f⁴ to the back of the bed or table B, and the upper end of said finger f³ is arranged 90 to be acted upon a cam f⁵, fixed to the rear face of the frame a upon an upward movement of said bed or table B to withdraw or pull back the detent-plate f, and a suitable spring is arranged to force said detent-plate 95 forward, as shown in Fig. 4, upon the downward movement of the bed or table B.

The heel-blank-ejecting mechanism of the machine of the drawings is arranged to discharge the compressed heel upon the downward movement of the bed or table B, and said mechanism is preferably arranged to eject the compressed heel from the dies D from the same side at which the heel-blank was fed to said dies, and this ejection of the compressed heel preferably takes place a little 100 in advance of the time of the complete downward movement of the bed or table B, so that the compressed heel will be discharged from the dies at a point above the plane of movement of the heel-blank which is being fed to the dies D, so that the compressed heel as it is ejected from the dies will be conveyed out of the machine by a deflector or chute (not shown) and will not interfere with the heel-blank which is resting upon the table E preparatory to being fed by the feeding-slide e². The heel-blank-ejecting mechanism of the machine of the drawings comprises a reciprocating ejecting-rod h, which is arranged to 110 have a movement back and forth along a guideway h', formed in an arm h*, which is secured to the rear side of the bed or table B in any suitable manner, said ejector-rod passing through an aperture h², formed in 115 the rear flange d⁴ in line with the medial line of the opening between the dies D, whereby when the dies shall be opened, as shown in Fig. 4, to release the compressed heel the ejector-rod h may be moved forward and 120 strike the back of the heel, forcing it out of the dies D.

125

130

The ejector-rod h is preferably arranged to be moved in one direction along the guide-way h' toward the dies D by means of a spring, whereby it will impart a sharp and quick blow to the back of the heel, knocking the heel from the dies D, and the ejector-rod is moved in the opposite direction against the tension of the spring and locked in its outer position under spring tension until the downward movement of the bed or table B shall have reached a point where it is desired to eject the compressed heel. To secure the above-suggested result, the ejector-rod h in the machine of the drawings is connected by means of a link h^3 to an arm or lever h^4 , said link h^3 being pivotally connected at one end to the ejector-rod h and at its opposite end to the arm or lever h^4 , as clearly shown in Fig. 6 of the drawings. The arm or lever h^4 is fixedly secured to a rock-shaft h^5 , arranged to rock in suitable bearings h^6 , carried by suitable brackets h^7 , secured to the rear face of the bed or table B. The arm h^4 is moved toward the bed or table B to cause the ejector h to knock the compressed heel from the die D by a suitable spring h^8 , one end of which is secured to the arm h^4 and the other end to the back of the bed or table B, and to move the arm h^4 in the opposite direction to retract the ejector h the shaft h^5 is projected beyond its bearing h^6 at one end (see Fig. 4) and is provided with a finger h^9 , fixedly secured to the end thereof, said finger h^9 arranged to be engaged by a pawl h^{10} , held in the path of movement of the finger h^9 , as the bed or table B moves up and down, whereby the shaft h^5 will be caused to rock in its bearings h^6 and move the arm h^4 outwardly against the tension of the spring h^8 to retract the ejector h , as shown in Fig. 6. The pawl h^{10} is carried by an arm h^{11} , which is fixedly secured to the rear face of the frame a in position to engage the finger h^9 upon a downward movement of the bed or table B, and, as shown in Fig. 7, the pawl h^{10} is pivotally mounted in a recess formed in the top of the arm h^{11} by a pin h^{12} , whereby said pawl h^{10} is arranged to swing upwardly to permit the free passage of the finger h^9 upon the upward movement of the bed or table B, but the pawl h^{10} is prevented from swinging downward, whereby upon the downward movement of the bed or table B it will engage the finger h^9 and rock the shaft h^5 to retract the ejector h , as before explained. The ejector is held in its retracted position under the tension of the spring h^8 by a suitable locking-dog or detent, which is arranged to be tripped to release the ejector mechanism at a suitable point in the downward travel of the table B, the pawl and its tripping mechanism being arranged and operated as follows: The locking-dog h^{12*} is carried by a shaft h^{13} , which is mounted to rock in suitable bearings h^{14} , formed in the arms or brackets h^7 , and in a bracket h^{15} , which, as in the case of the brackets h^7 , is secured to and movable with the bed or table B. The lock-

ing-dog h^{12*} is arranged to engage a notched collar h^{16} , carried by the shaft h^5 , said dog being pressed against the collar h^{16} by a spring h^{17} , connected at one end to an arm h^{18} , rigidly secured to and projected from the shaft h^5 , the spring h^{17} causing the shaft to rock in its bearings h^{14} and holding the locking-dog h^{12*} in position to engage the notch in the collar h^{16} , as clearly shown in Fig. 6 of the drawings, whereby the arm h^4 and the ejector h will be held in their retracted position under the tension of spring h^8 , as before described.

In order to trip the locking-dog h^{12*} upon the downward movement of the bed or table B to release the arm h^4 and the ejector h , the shaft h^{13} is projected beyond its bearing h^{14} in the bracket h^{15} , as clearly shown in Fig. 4 of the drawings, and upon the outer end of said shaft is fixedly secured a finger h^{19} , arranged to be engaged by a pawl h^{20} , pivotally supported in a recess in a vertical arm or standard h^{21} , which is secured to the top of one of the side frames of the fixed frame of the machine in such position that upon the downward movement of the bed or table B the finger h^{19} will be engaged by the pawl h^{20} and cause a slight rotation of the shaft h^{13} in its bearings, which acts to discharge the locking-dog h^{12*} from the notch in the collar h^{16} on the shaft h^{13} and permit the spring h^8 to quickly move the arm h^4 and the ejector h toward the dies D and to deliver a sharp and quick blow upon the heel in said die to remove it therefrom.

The above-described arrangement is such that with the ejector h retracted, as in Fig. 6, the bed or table B will be moved vertically to cause the dies D and C to compress the heel, and upon a downward movement when the table B has reached the point where it is desired to eject the heel from the dies D the arm h^{19} will be engaged by the pawl h^{20} to slightly turn the shaft h^{13} and disengage the locking-dog h^{12*} from the notched collar h^{16} , permitting the spring h^8 to move forward the arm h^4 and the ejector-rod h to deliver a sharp quick blow upon the heel and discharge it from the dies D. Upon the further downward movement of the bed or table B the finger h^9 upon the end of shaft h^5 will be engaged by the pawl h^{10} to turn the shaft h^5 and retract the arm h^4 and the ejector to again set the same, the spring h^{17} causing the locking-dog to engage the notched collar h^{16} and hold the ejector retracted, as above described. Upon the upward movement of the bed or table B the arms h^9 and h^{19} pass the pawls h^{10} and h^{20} , said pawls lifting and permitting the passage of the arms h^9 and h^{19} without disturbing the ejector, and after the arms h^9 and h^{19} have passed above the pawls h^{10} and h^{20} they will drop back in position to release and reset the ejector, as before described.

The operation of my invention is as follows: The bed or table B being in its lowest position, as shown in Figs. 1 and 2, and the dies D being open, with the ejector mechanism

set as shown in Fig. 6, the heel-blank is placed upon the table E in front of the feeding-plate e^2 with the breast edge of the heel-blanks bearing against the edge e^3 of the feeding-plate e^2 and with one side of the heel-blank bearing against the guide-plate e^{17} . The operator now places his foot upon the treadle a^{16} , thus causing the pulley A^3 to be moved toward the wheel A^4 and the clutch-faces a^5 and a^6 brought into contact, whereby motion is imparted to the driving-shaft A' and to the several parts of the machine. The rotation of the driving-shaft A' acts through the pinion a^{17} and the gear a^{18} to impart a rotation to the crank-shaft A^2 and through the medium of the link b^{10} and the toggles b^2 and b^3 to impart a vertical movement to the bed or table B to carry the bed or table and the dies and heel-blank thereon toward the heel-seat die C. Just prior to the vertical movement of the table B the tappet e^{13} has acted upon the roll e^{12} , carried by the arm e^{11} of the bell-crank lever, which through the connecting-rod e^7 oscillates the lever e^5 to move forward toward the dies D the feed-plate e^2 , feeding the heel-blank resting upon the table E into the opening between the dies D, the back portion of the heel-blank being engaged by the forward end of the detent-plate f , as hereinbefore described. After the tappet e^{13} has passed the roll e^{12} the spring e^{14} acts to quickly return the bell-crank lever and the feed-plate e^2 to their normal condition, as shown in Fig. 4 of the drawings. As the bed or table B moves upwardly the ends of the levers D' move along the top of the bed or table and engage the outer sides of the die-carriers d^2 and in the further upward movement of the bed or table force the die-carriers toward each other against the tension of the springs d^7 to bring the dies D forcibly against the sides and back of the heel to compress and shape the same. As the bed or table approaches the heel-seat die C the bevelled finger c^{17} comes in contact with the inner edge of the plate c^{19} and moves inwardly the breast-molding plate c^{14} to cause it to enter the recess c^{18} , and the continued upward movement of the bed or table B causes the heel-seat die C to come in contact with the upper surface of the heel-blank, and at the extreme limit of the upward movement of the bed or table B the heel-blank will be forcibly compressed between the heel-seat die C and the upper surface of the bed or table B or the tread-molding plate b^* thereon and the side-compressing dies D and the breast-plate c^{14} . During the upward movement of the bed or table B the rod f^3 strikes the inclined cam-surface f^3 and is swung outwardly against the tension of its spring, retracting the detent-plate f and withdrawing its forward end from its position over the recess between the dies D. The continued rotation of the crank-shaft a^2 now acts to break the toggles b^2 and b^3 and to lower the bed or table B, and as said bed or table is lowered the heel is relieved

from pressure by the movement of the ends of the levers D' away from the die-carriers d^2 , said die-carriers being moved away from each other to open the dies D by the springs d^7 , as before explained, the movement of the dies D away from each other being just sufficient to clear the heel and relieve the same from pressure, as heretofore explained. As the bed or table continues to move downwardly the finger h^9 on the shaft h^{13} will be engaged by the pawl h^{20} to trip the locking-dog h^{12*} and permit the spring h^8 to throw forward the ejector-rod h , which strikes the back of the heel a sharp and quick blow, ejecting it from between the dies D, as before described. This action of the ejector takes place before the bed or table B has reached the limit of its movement in the downward travel, and the finished heel is arranged to be guided from the machine by a suitable deflector or chute. (Not shown.) As the bed or table continues its downward movement and immediately after the ejector has discharged the heel from the machine the finger h^9 of the shaft h^5 will be engaged by the pawl h^{10} to rock the shaft h^5 and retract the ejector h against the tension of the spring h^8 , said ejector and the arm h^4 being moved to the position shown in Fig. 6, where they will be held by the locking-dog h^{12*} , which is drawn into engagement with the notched collar h^{16} by the spring h^{17} . While the bed or table B has been traveling downward the operator has placed another heel-blank in position upon the table E ready to be fed into the space between the dies D, and the operation, as before described, is again repeated.

Having fully described my invention and its mode of operation, I claim as new and desire to secure by Letters Patent of the United States—

1. In a heel-compressing machine, the combination with the vertically-movable table, of side-compressing dies mounted thereon, a heel-blank-feeding device, and means to actuate the same to feed a heel-blank between the side-compressing dies at one level, and a heel-blank-ejecting device and means to actuate the same to eject the compressed heel-blank from between the side-compressing dies at a different level, substantially as described.

2. In a heel-compressing machine, the combination with the vertically-movable table, of side-compressing dies mounted thereon, of a heel-blank-feeding mechanism arranged to feed a heel-blank between the side-compressing dies when the table is substantially in its lowermost position, and a heel-blank-ejecting device and mechanism to actuate the same to cause it to strike and eject the heel-blank from between said dies during the downward movement of the table, substantially as described.

3. In a heel-compressing machine, the combination with a vertically-movable table carrying the side-compressing dies, of a heel-seat die mounted on a fixed support, and a swing-

ing breast-molding plate, substantially as described.

4. In a heel-compressing machine, the combination with the heel-seat die, of a vertically-
5 adjustable holder for such die, said die being
yieldingly mounted in its holder, substantially
as described.

10 5. In a heel-compressing machine, the combination with the side-compressing dies, of
means to open and close the same, a detent-
plate arranged to project over the space be-
tween said dies, and means to withdraw the
detent-plate when said dies are closed, sub-
stantially as described.

15 6. In a heel-compressing machine, the combination with a fixed die and a die movable
toward and from the fixed die, of an ejector
arranged to discharge a compressed heel-
blank from between the dies in a plane sub-
stantially at right angles to the line of move-
ment of the movable die, and means actuated
by the movements of the movable die to ac-
tuate the ejector, substantially as described.

20 7. In a heel-compressing machine, the combination with a fixed male die, of a female
die movable toward and from the male die, an
ejector arranged to discharge a compressed
heel from between said dies in a plane sub-
stantially at right angles to the line of move-
ment of the female die, means to retract said
ejector and a spring to advance said ejector
to cause it to strike the heel, substantially as
described.

25 8. In a heel-compressing machine, the combination with a heel-compressing die, of an

ejector arranged to discharge the heel from
said die, a spring to throw said ejector against
the heel, means to retract said ejector, a locking-dog
to hold said ejector retracted under
the tension of the spring, and means to re-
lease said locking-dog, substantially as de-
scribed.

40 9. In a heel-compressing machine, the combination with a heel-compressing die mounted
on a movable support, of an ejector arranged
to discharge the heel from said die, a spring
to force said ejector against the heel in said
die, a locking-dog to hold said ejector retracted
under spring tension, and means operated by
the movement of the support of the die to re-
lease said locking-dog and retract the ejector,
substantially as described.

45 10. In a heel-compressing machine, the combination with a vertically-movable table and
a heel-compressing die mounted thereon, of a
feeding-plate and means to actuate the same
to feed a heel-blank to the heel-compressing
die, an ejector to remove the heel-blank, and
means actuated by the movement of the table
50 to move the ejector toward and from the die
substantially at right angles to the movement
of the table to discharge the heel from the
same side of the die at which it enters the die,
substantially as described.

55 In testimony whereof I affix my signature
in presence of two witnesses.

WILLIAM J. YOUNG.

Witnesses:

WALTER H. SOUTHWICK,
HARRIET L. BEAN.
